IGNITION SYSTEM.

1,352,431.

Specification of Letters Patent. Patented Sept. 14, 1920.

Application filed September 26, 1910. Serial No. 583,857.

To all whom it may concern:

Be it known that I, FRANK CONRAD, a citizen of the United States, and a resident of Pittsburgh, in the county of Allegheny and 5 State of Pennsylvania, have invented a new and useful Improvement in Ignition Systems, of which the following is a specification.

My invention relates to electrical ignition 10 systems and particularly to such systems as are employed for igniting the charges of explosion engines or for similar purposes.

The object of my invention is to provide a 15 system of the character indicated which shall be unusually effective in operation, and which will permit of the employment of any convenient source of energy, which source may also supply current for other purposes, as for lighting, etc.

20 Figure 1 of the accompanying drawing illustrates, diagrammatically, a system that embodies my invention, and Fig. 2 is a similar view of a modified form of the system of Fig. 1.

25 The system comprises a spark plug having insulated and separated terminal members 2 and 3 that are respectively connected to the terminals of any suitable source of current, such as a battery 1, impedance coils 4 and 5 30 being respectively included in the connections between the terminals and the source. The spark plug is shown with its lower end threaded, so that it may be screwed into the cylinder of an engine with the terminals 2 and 3 projecting thereinto, but it will be understood that the terminals 2 and 3 may, if desired, constitute parts of any other device than the spark plug of an explosion engine. For the sake of simplicity, the impedance coils 4 and 5 are shown as wound 40 upon a common core 6, though, if desired, they may be separate and independent devices.

45 The source 1 primarily supplies current to the primary winding 8 of a transformer or induction coil 9 having a secondary winding 10, an interrupting device 11 and two impedance coils 12 and 13, respectively, being included in circuit with the primary winding 8. The interrupting device 11 conveniently 50 comprises a stationary terminal member 14 and a resilient arm 15, that is normally maintained in engagement with the terminal 14, and is operated into and out of engagement therewith, by means of a cam or seg-

mental disk 16, that is actuated by some movable part of the engine or other machine in connection with which the system is employed. A condenser 17 is connected in parallel with the interrupting device 11 and 60 the primary winding 8.

In shunt to the secondary winding 10 is an auxiliary spark device 18 having permanently separated, but adjustable, terminal members 19, and, in series with, and upon 65 opposite sides of, the said winding, are condensers 20 and 21, respectively, the terminals of the secondary circuit being connected to the terminals 2 and 3 of the spark plug.

In the operation of the system, current is 70 supplied from the source 1 to the primary winding 8 of the transformer or induction coil 9 by way of a circuit comprising the parts bearing reference numerals 1, 5, 13, 8, 14, 15, 12 and 6, this circuit being closed when 75 the cam or disk 16 occupies the position shown. Although the spark plug is then included in circuit with the source, no current is supplied thereto, because the terminals 2 and 3 thereof are separated and the potential 80 of the source is insufficient to overcome the resistance of the gap between them. The condensers 20 and 21 also prevent current from being supplied from the battery to the secondary winding 10 of the transformer or 85 induction device.

As the cam or disk 16 is rotated, the terminal members 14 and 15 of the interrupter 11 are quickly separated, and a very high electromotive force is induced in the secondary 90 winding 10, which causes a discharge between the terminals 19 of the auxiliary spark device 18. This discharge causes an oscillatory electromotive force of very high voltage and frequency in the secondary circuit, 95 which electromotive force is sufficient to overcome the high resistance of the gap between the terminals of the spark plug and to cause a discharge between them. The circuit in which the oscillations occur comprises the parts bearing reference numerals 18, 20, 2, 3 and 21, which, obviously, is of very low impedance in order that the oscillatory electromotive force may not be greatly resisted or impeded. The high frequency oscillations are prevented from traversing the battery 1 by the impedance coils 4 and 5, and from traversing other parts of the primary circuit by the impedance coils 12 and 13.

After the oscillatory electromotive force has

caused a discharge across the gap between the terminal members 2 and 3, current from the battery or source 1, and a discharge of the energy stored in the impedance devices 5 5, 6, 12 and 13 follow the oscillatory discharge and produce a very hot arc of considerable volume. Thus, the high-frequency discharge insures breaking down the resistance between the terminal members 2 and 3, 10 and, since current directly from the source follows the discharge, a hot arc between the terminals is also insured, so that the system provides a very reliable and efficient ignition means for use with explosion engines and similar apparatus. 15

In Fig. 2, the circuits of the system are so arranged as to dispense with the impedance coils 12 and 13, the coils 4 and 5 serving not only to prevent the high-frequency electromotive force from traversing 20 the battery or source, but also from traversing the circuit of the primary winding of the transformer 9.

I claim as my invention:

25 1. An ignition system comprising a source of current, a primary circuit connected to the source and including an interrupter, a secondary circuit inductively related to the primary circuit, a spark device having permanently separated terminal members in shunt to the secondary circuit, and a spark plug connected between the terminals of both the source and the secondary circuit.

30 2. An ignition system comprising a source of current, a primary winding connected to the source, an interrupter in series with the primary winding, a secondary winding inductively related to the primary winding, a spark device having permanently separated terminal members in shunt to the secondary winding, and a spark plug connected between the terminals of both the source and the secondary winding.

35 3. An ignition system comprising a source of current, a primary circuit connected to the source and including an interrupter, a secondary circuit inductively related to the primary circuit and including a permanently open gap, a spark plug connected 40 between the terminals of both the source

and the secondary circuit, and condensers in the connections between the spark plug and the secondary circuit.

4. An ignition system comprising a source of current, a primary circuit connected to the source and including an interrupter, a secondary circuit inductively related to the primary circuit and including a permanently open gap, a spark plug connected between the terminals of both the source and the secondary circuit, impedance devices interposed in the connections between the source and the spark plug, and condensers in the connections between the spark plug and the secondary circuit. 65

5. An ignition system comprising a source of current, a device having inductively related primary and secondary windings, an interrupter in series with the primary winding, a condenser in shunt to the primary winding and the interrupter, an auxiliary spark device in shunt to the secondary winding, impedance coils interposed between both the source and the primary winding and the secondary winding and the auxiliary spark device, and a spark plug connected between the terminals of both the source and the secondary winding. 70

6. An ignition system comprising a source of current, a device having inductively related primary and secondary windings, an interrupter in series with the primary winding, a condenser in shunt to the primary winding and the interrupter, an auxiliary spark device in shunt to the secondary winding, impedance coils interposed between both the source and the primary winding and the secondary winding and the auxiliary spark device, a spark plug connected between the terminals of both the source and secondary winding, and impedance devices interposed in the connections between the spark plug and the source. 80 85

In testimony whereof, I have hereunto subscribed my name this 23rd day of Sept., 90 95 1910.

FRANK CONRAD.
